UNITED STATES PATENT OFFICE.

LUTHER M. BRADBURY, JR., OF QUINCY, MASSACHUSETTS.

SLED-BRAKE.

SPECIFICATION forming part of Letters Patent No. 319,950, dated June 16, 1885.

Application filed February 24, 1885. (No model.)

To all whom it may concern:

Be it known that I, LUTHER M. BRADBURY, Jr., of Quincy, in the county of Norfolk, State of Massachusetts, have invented a certain new and useful Improvement in Sleds, of which the following is a description sufficiently full, clear, and exact to enable any person skilled in the art or science to which said invention appertains to make and use the same, reference being had to the accompanying drawings, forming a part of this specification, in which—

Figure 1 is a side elevation of a sled embodying my improvement, the brake being represented as elevated or out of use; and Fig. 2, a corresponding view showing the brake depressed or in use.

Like letters of reference indicate corresponding parts in the different figures of the drawings.

My invention relates to that class of sleds which are provided with brakes; and it consists in a novel construction and arrangement of the parts, as hereinafter more fully set forth and claimed, by which a more effective and otherwise desirable device of this character is produced than is now in ordinary use.

The nature and operation of the improvement will be readily understood by all conversant with such matters from the following explanation, its extreme simplicity rendering an elaborate description unnecessary.

In the drawings, A represents the body or platform of the sled; B, the forward runners; C, the hind runners, and E the tongue or shafts, these parts being of the ordinary form and construction, except as hereinafter specified.

Arranged to work vertically in one of the runners C there is a serrated bar, E, said bar being inclined or beveled at its lower end, x, and adapted to engage the snow or ice when depressed. Pivoted loosely by the staple m to the bar H there is a toothed segment, J, adapted to engage the serrated bar E, said segment and bar being also connected and kept in engagement by a link, K, which passes

loosely through holes in said parts. A vertically-arranged lever, L, is pivoted at f to the forward end of the platform A, and jointed 50 to the lower end of said lever there is a horizontally-arranged connecting-rod, N, the rear end of which is jointed to the segment J. A spring, z, is attached to the upper side of the runner C, the free end of said spring pressing 55 on the top of the bar E to prevent it from rattling, and also assisting to force the same downwardly through said runner when the lever L is pushed forward, as hereinafter described.

In the use of my improvement, the lever L being arranged vertically, or nearly so, and secured by the pivoted catch Q, and the bar E elevated, as shown in Fig. 1, if, now, it is desired to apply the brake to stop or retard the 65 forward movements of the sled, the catch Q is detached from the lever and the lever forced forward, as shown in Fig. 2, causing the segment J to partially rotate on its pivotal support m, and force the bar E downward through 70 the runner C into engagement with the snow or ice in a manner which will be readily obvious without a more explicit description.

I do not confine myself to pivoting the segments J to the bar H, as it may be pivoted 75 directly to one of the runners C, if desired; neither do I confine myself to the use of two pairs of runners, as one pair may be employed, if preferred.

Having thus explained my invention, what I 80 claim is—

In a sled, the combination of the vertically-sliding serrated brake-bar E, a spring, z, pressing on said bar, the segment J, intermeshing therewith, the staple m, passing through said segment and into the frame of the sled, the link K, connecting said segment and brake-bar, rod N, connected to said segment, and the pivoted lever L, connected to said rod, substantially as described.

LUTHER M. BRADBURY, JR.
